RAILWAY TRAFFIC CONTROLLING
APPARATUS

Henry S. Young, Wilkinsburg, Pa., assignor to
The Union Switch & Signal Company, Swiss-
vale, Pa., a corporation of Pennsylvania

Application October 13, 1932, Serial No. 637,617

12 Claims. (Cl. 246—160)

My invention relates to railway traffic controlling apparatus, and particularly to apparatus of the type involving a railway switch and signals governing traffic movements over the switch.

5 More specifically, my invention relates to apparatus wherein a train approaching a spring type switch in a given direction locks the switch, and a train approaching the switch in an opposite direction unlocks the switch or retains the switch
10 in an unlocked condition. My invention also relates to means for directing traffic movements in the first direction over the switch only if the switch is locked, and to means for directing traffic movements in the second direction over the switch
15 only if the switch is unlocked.

I will describe two forms of apparatus embodying my invention, and will then point out the novel features thereof in claims.

In the accompanying drawings, Fig. 1 is a dia-
20 grammatic view showing one form of apparatus embodying my invention. Fig. 2 is a diagrammatic view showing a modification of the apparatus shown in Fig. 1, and also embodying my invention.

25 Similar reference characters refer to similar parts in each of the views.

Referring to the drawings, the reference character **X** designates a stretch of single track railway which is connected with tracks **Y** and **Z** by means of a switch **F¹**. In Fig. 1, tracks **Y** and **Z** may be either a stretch of double track or they may be passing tracks, as shown in Fig. 2, the opposite ends of which are connected with stretch **X** by a second switch **F²**.

35 Each of these switches may be biased to its normal position, in which it is shown, by some suitable means which may, for example, be of the well known spring type. Each of these switches may be manually movable to its reverse position by suitable means not shown in the drawings, and may also be movable to its reverse position by a train going over the switch in the trailing direction, that is, switch **F¹** may be movable to its reverse position by a train going over it from track **Z** to stretch **X**, and switch **F²** may be movable to its reverse position by a train going over it from track **Y** to stretch **X**.

50 Rails **1** and **1^a** of stretch **X** and of tracks **Y** and **Z** are divided by means of insulated joints **3** into sections **A—B**, **B—C**, **C—D**, and **C^a—D^a**. In Fig. 2, there is also an additional section **D—E**. A track circuit is provided for each of these sections, and includes a track battery **4** connected
55 across the rails adjacent one end of the section

and a track relay designated by the reference character **R** with a distinguishing exponent and connected across the rails adjacent the other end of the section.

5 Signals, each of which is designated by the reference character **S** with a distinguishing exponent, govern traffic movements in both directions over switches **F¹** and **F²**. Signals **S²** and **S³** govern traffic movements in the trailing direction over switch **F¹** from tracks **Y** and **Z**, respectively, to stretch **X**, and signal **S¹** governs traffic movements in the opposite or facing direction over switch **F¹** from stretch **X** to track **Y**. Similarly, signals **S⁴** and **S⁵**, shown in Fig. 2, govern traffic movements in the trailing direction over switch **F²** from tracks **Y** and **Z**, respectively, to stretch **X**, and signal **S⁶** governs traffic movements in the opposite or facing direction over switch **F²** from stretch **X** to track **Z**. As here shown, each of the signals **S** is of the color light type, although it is to be understood that my invention is not limited to this particular type of signals. In Fig. 1, the signals **S** are shown having a red or stop lamp **R** and a green lamp **G** indicating "clear". In Fig. 2, the signals are shown having also a yellow lamp **Y** indicating "caution".

20 Circuits and other parts of the apparatus are shown for controlling switch **F¹** and signals **S¹**, **S²** and **S³**. Switch **F²**, shown in Fig. 2, and signals **S⁴**, **S⁵** and **S⁶** associated with this switch 25 may be controlled similarly to switch **F¹** and the associated signals **S³**, **S²** and **S¹**, respectively, also shown in Fig. 2.

A lock bar **d** is rigidly secured to switch **F¹** for engagement by a dog **a**, by means of which 35 the switch may be locked in its normal position only. Dog **a** is actuated by a motor **G** which may be of any suitable type but which, as here shown, is an electric motor having an armature 40 and a field winding **22**.

In conjunction with dog **a**, motor **G** actuates a contact **21** which is closed in a reverse operating circuit for motor **G** at all times except when dog **a** reaches its final position for locking bar **d**, and which is closed in a normal operating circuit for motor **G** at all times except when dog **a** is in its normal position out of engagement with bar **d**. Dog **a** actuates a contact **47** which is closed only when dog **a** is out of engagement with bar **d**, and also actuates a contact **26** which 50 is closed only when dog **a** is in its final position for locking bar **d**.

Movement of motor **G** and clearing of signals **S** are controlled by trains approaching switch **F¹**. A train approaching switch **F¹** in the facing 55

direction, that is, from left to right as shown in the drawings, will set motor G into operation to lock switch F¹ in the normal position, whereas a train approaching switch F¹ in the trailing direction, that is, from right to left will, in Fig. 1, set motor G into operation to unlock switch F¹ if that switch is locked. A train approaching switch F¹ in the facing direction, which I will also assume to be the eastbound direction, will cause signal S¹ to "clear" as soon as motor G has locked switch F¹ in the normal position. A train approaching switch F¹ in the trailing or westbound direction will cause signal S³ or signal S² to "clear" when switch F¹ is unlocked.

15 In Fig. 2, a train, after moving over switch F¹ in the facing direction, will set motor G into operation to unlock the switch, and hence a train approaching switch F¹ in the trailing direction will, in Fig. 2, merely clear signal S² or signal S³ since switch F¹ will be already unlocked.

20 Switch F¹ actuates a circuit controller commonly known as a point detector, which in Fig. 1 has only one contact 7, and which in Fig. 2 has a second contact 63 in addition to a contact 7. 25 Each of these contacts is closed only if the switch points of the associated switch are in their proper condition while the switch is in its normal position.

25 A hand crank N is provided adjacent switch F¹, primarily for emergency use by a trainman to manually move dog a out of engagement with bar d when it becomes necessary to manually reverse the switch for a traffic movement in the eastbound direction from stretch X to track Z. 30 For this use, the trainman will place crank N in the position in which it is shown in dash lines in the drawings, thereby displacing contact 8 to its open position r. He will then operate crank N to disengage dog a from bar d. Contact 35 8 in Fig. 1, upon becoming opened, breaks the pick-up and stick circuits for a relay I^G which, being thereby deenergized, opens the operating circuits for motor G. Relay I^G also controls a pick-up circuit for a track stick relay R^{2S} for section B—C. In the arrangement shown in Fig. 40 2, contact 8, upon becoming opened, breaks the pick-up and stick circuits for a relay W^R which controls motor G.

45 Referring to Fig. 1 of the drawings, a train, upon approaching switch F¹ from the left, that is, in the facing direction, will cause an approach relay P^L to become energized, and this will cause motor G to operate dog a into engagement with bar d to lock switch F¹ in the normal position. 50 Upon completion of this locking operation for switch F¹, a slow release relay H¹ will become energized for clearing signal S¹.

55 The train, upon then passing signal S¹, will cause a directional stick relay I^L to become energized. This relay, when energized, prevents the clearing of signal S² while a train is moving in the eastbound direction in section C—D, and permits the clearing of signal S³ if another train is in section C^a—D^a.

60 65 A westbound train approaching switch F¹ on track Z will cause a second approach relay P^R to become energized for causing motor G to operate dog a out of engagement with bar d if dog a has been operated to the position for locking bar d. With switch F¹ thus unlocked and with relay P^R energized, a signal control relay H³ will become energized for clearing signal S³.

70 75 A westbound train, upon passing signal S³ while signal S³ is displaying its proceed indication, will cause a second directional stick relay

I^R to become energized. The purpose of this relay is to prevent any automatic action toward locking switch F¹ or clearing signal S¹ while a train is moving in the westbound direction in section A—B. A push button contact U is provided for use when necessary to deenergize relay I^R, after a train movement from track Z to stretch X, for permitting motor G to lock switch F¹ and for permitting signal S¹ to "clear" for the train to proceed eastward to track Y.

10 Relays H¹, H² and P^R are of the slow releasing type in order that they may control the directional relays I^L and I^R in a given manner by circuits which will be traced hereinafter.

15 Referring now to Fig. 2, each of the signals S is here shown controlled by a slow release neutral relay designated by the reference character H with a corresponding exponent, and by a polarized relay designated by the reference character T with a corresponding exponent. When an eastbound train approaches switch F¹, relay T² for controlling signals S² and S³ will become deenergized, causing relay H³ to also become deenergized. Relay H³, upon becoming deenergized, causes signal S³ to display the stop 25 indication. The deenergization of relays T² and H³ causes control element 59 of a time element device M to become energized. Device M, upon the lapse of a measured period of time after becoming energized, closes its contact 60 which 30 causes relay W^R to become energized. Relay W^R then completes a circuit for causing motor G to operate dog a to lock the bar d. Upon the completion of this operation of dog a, relay H¹ will become energized and cause signal S¹ to display a caution or a clear indication according as 35 relay T¹ is energized in the reverse or the normal direction, respectively. After the eastbound train has proceeded through sections A—B and B—C, relay W^N will become energized and cause 40 motor G to operate dog a to unlock bar d. Relay H³ will then become energized and cause signal S³ to display either a caution or a clear indication according as relay T² is energized in the reverse or the normal direction, respectively.

45 Traffic direction stick relays I^L and I^R are in part controlled similarly to the corresponding relays of Fig. 1. Relay I^L, in turn, controls a third directional stick relay I^{LP}.

50 The control circuit for relay T⁶ for signal S⁶ is included in order to show how the control of this relay is affected by the apparatus associated with switch F¹. Signal S⁶ will be controlled by relay T⁶ similarly to the manner in which signal S¹ is controlled by relay T¹.

55 Switch F² may also be of the spring type, and may be controlled similarly to the manner in which switch F¹ is controlled. Signals S⁴, S⁵ and S⁶ may be controlled similarly to signals S³, S² and S¹, respectively. Relay T¹ would then be 60 controlled by the apparatus at switch F² similarly to the manner in which relay T⁶ is shown controlled by the apparatus at switch F¹.

Having described, in general, the arrangement and location of the various parts of the apparatus embodying my invention, I will now describe in detail the operation of the apparatus.

65 As shown in Fig. 1, all parts are in their normal condition, that is, switch F¹ is in its normal position, each of the signals S is displaying a stop 70 indication; each of the track sections is unoccupied; with the track sections unoccupied, the track relays R are energized; dog a is out of engagement with bar d; and relays H, P, I^L and I^R are deenergized. The red lamp R of each of 75

the signals S is lighted, for displaying the stop indication, by a circuit which includes the back point of a contact 11 of its control relay H. Relay I^G is energized by its stick circuit which passes from terminal b of a source of current not shown in the drawings, through point detector contact 7 of switch F¹, contact 8 operated by crank N, contact 9 of relay I^G, and the winding of relay I^G to terminal o of the same source of current. Relay R^{2S} is energized by both its pick-up and its stick circuit. The pick-up circuit for relay R^{2S} includes track battery 4 and the rails of section B—C, and passes through front contact 6 of relay I^G and the winding of relay R^{2S}. The stick circuit for relay R^{2S} is the same as the pick-up circuit except that it includes contact 5 of relay R^{2S} instead of contact 6 of relay I^G.

I will now assume that an eastbound train enters section A—B, causing relay R¹ to become deenergized. Relay R¹ thereupon completes a circuit for energizing approach relay P^L, passing from terminal b, through contact 7 of switch F¹, back contact 12 of relay P^R, back contact 13 of relay H², back contact 14 of relay I^R, contact 15 of relay R^{2S}, contact 16 of relay R¹, and the winding of relay P^L to terminal o. Relay P^L, upon becoming energized, completes a reverse operating circuit for motor G, passing from terminal b, through contact 7 of switch F¹, contact 17 of relay P^L, armature 18 of motor G, contact 19 of relay I^R, contact 20 of relay P^L, contact 21 of motor G, and field winding 22 of motor G to terminal o. Motor G thereupon moves dog a into position to engage and lock bar d. Upon the completion of this locking movement of dog a, contact 21 opens the reverse operating circuit traced for motor G, and relay H¹ becomes energized by a circuit passing from terminal b, through contact 25 of relay H³, contact 26 of dog a, contact 27 of relay P^L, and the winding of relay H¹ to terminal o. Relay H¹ thereupon opens, at the back point of its contact 11, the circuit for red lamp R of signal S¹, and closes, at the front point of its contact 11, the circuit for green lamp G of signal S¹.

The train, upon entering section B—C, deenergizes relay R^{2S} which thereupon opens, at its contact 15, the circuit traced for relay P^L. Relay P^L, upon becoming deenergized, opens, at its contact 21, the circuit traced for relay H¹. Relay H¹, being slow releasing, does not at once open its contact 30 at the front point, and hence a pick-up circuit is completed for a brief period of time for energizing relay I^L, passing from terminal b, through contact 28 of relay R^{2S}, front point of contact 30 of relay H¹, and the winding of relay I^L to terminal o. Relay I^L, upon becoming energized, completes its own stick circuit passing from terminal b, through contact 28 of relay R^{2S}, contact 31 of relay I^L, and the winding of relay I^L to terminal o. Relay R^{2S}, upon becoming deenergized, also completes a pick-up circuit for relay I^G, which is the same as the stick circuit previously traced for this relay except that it includes contact 10 of relay R^{2S} instead of contact 9 of relay I^G.

As the train enters section C—D, relay R³ becomes deenergized, thereby completing a second stick circuit for relay I^L, passing from terminal b, through contact 29 of relay R³, back point of contact 30 of relay H¹, contact 31 of relay I^L, and the winding of relay I^L to terminal o. Relay I^L therefore continues energized until the train leaves section C—D. With relay I^L energized, its

contact 39 is open in a circuit for energizing relay H², and hence relay H² can not become energized while the train is receding from signal S². Signal S² can therefore not clear as long as the eastbound train is in section C—D.

If, however, a westbound train enters section C—D^a while the eastbound train is still in section C—D, approach relay P^R will become energized by a circuit passing from terminal b, through contact 32 of relay P^L, contact 33 of relay R¹, contact 34 of relay R^{2S}, contact 35 of relay R⁴, contact 37 of relay I^L, and the winding of relay P^R to terminal o. With relay P^R thus energized, a circuit will be completed for causing motor G to return dog a to its normal position out of engagement with bar d. This circuit for motor G passes from terminal b, through contact 23 of relay P^R, contact 19 of relay I^G, armature 18 of motor G, contact 24 of relay P^R, contact 21 of motor G in its reverse position, and field winding 22 of motor G to terminal o. As soon as motor G completes the operation of dog a to its unlocking position, relay H³ will become energized by a circuit passing from terminal b, through contact 46 of relay H¹, contact 47 of dog a, contact 48 of relay P^R, and the winding of relay H³ to terminal o. Relay H³, upon becoming energized, opens, at the back point of its contact 11, the circuit for the red lamp of signal S³, and completes, at the front point of its contact 11, the circuit for green lamp G of signal S³, thus permitting the westbound train in section C—D^a to proceed while an eastbound train is still in section C—D.

The westbound train, upon passing signal S³, deenergizes relay R^{2S} which then opens, at its contact 34, the circuit traced for relay P^R. Relay P^R thereby becomes deenergized but, on account of being slow releasing, causes a pick-up circuit to be completed for a brief period of time for energizing relay I^R, passing from terminal b, through contact 40 of relay R^{2S}, front point of contact 42 of relay P^R, the winding of relay I^R, and push button contact U to terminal o. Relay I^R, upon becoming energized, completes its own stick circuit passing from terminal b, through contact 40 of relay R^{2S}, contact 45 of relay I^R, the winding of relay I^R, and push button contact U to terminal o. The westbound train, while proceeding over switch F¹, forces switch F¹ to the reverse position since dog a is now out of engagement with bar d.

This train, upon entering section A—B, deenergizes relay R¹, thereby causing a second stick circuit to be completed for relay I^R, passing from terminal b, through contact 43 of relay R¹, contact 44 of relay H², back point of contact 42 of relay P^R, contact 45 of relay I^R, the winding of relay I^R, and push button contact U to terminal o.

Relay I^R therefore continues energized after the train leaves section B—C. The circuit for relay P^L, previously traced, therefore remains open at back contact 14 of relay I^R, and hence the reverse operating circuit for motor G remains open at contacts 17 and 20 of relay P^L, and the circuit for relay H¹ remains open at contact 27 of relay P^L, thus causing signal S¹ to continue to display a stop indication while the train is receding from this signal.

If, however, the train is to proceed eastward on track Y instead of continuing its westward movement, a trainman will now operate push button contact U to open the stick circuit for relay I^R. Relay I^R, upon becoming deenergized, permits relay P^L to become energized by its cir- 75

cuit previously traced, which thereupon causes motor G to lock switch F¹, after which signal S¹ will display its proceed indication.

I will now assume that a fast westbound train is to pass a slow westbound train. The slow train will be sent onto track Z, whereas the fast train will move over track Y. The slow train having arrived on section C^a—D^a before the fast train has arrived on section C—D, relay P^R will become energized by a second pick-up circuit which is the same as the pick-up circuit previously traced for this relay except that it includes contact 36 of relay R³ instead of contact 37 of relay I^L. With relay P^R energized, motor G will operate to disengage dog a from bar d if dog a is not already in its unlocking position. As soon as dog a is out of engagement with bar d, relay H³ will become energized by its circuit previously traced. Under this condition, relay I^L remains deenergized, and the train on track Y deenergizes relay R³, and hence relay P^R becomes deenergized since its pick-up circuits will be open at contact 36 of relay R³ and contact 37 of relay I^L. With relay P^R deenergized, the circuit for relay H³ is opened at contact 48 of relay P^R, and hence signal S³ will be caused to again display a stop indication. A circuit will now be completed, however, for energizing relay H², passing from terminal b, through contact 32 of relay P^L, contact 33 of relay R¹, contact 34 of relay R^{2S}, contact 38 of relay R³, contact 39 of relay I^L, and the winding of relay H² to terminal o. Relay H², upon becoming energized, opens, at the back point of its contact 11, the circuit for the red lamp of signal S², and completes, at the front point of its contact 11, the circuit for the green lamp G of signal S².

When the westbound train on track Y enters section B—C, a second pick-up circuit will, on account of relay H² being slow releasing, be completed for relay I^R, passing from terminal b, through contact 40 of relay R^{2S}, contact 41 of relay H², the winding of relay I^R, and push button contact U to terminal o. As the train proceeds westward through section A—B, relay I^R will continue energized by its second stick circuit previously traced, and will therefore prevent motor G from operating and signal S¹ from clearing. When the fast train has left section A—B, relay P^R will again become energized by its second pick-up circuit, thereupon causing relay H³ to become energized, which will cause signal S³ to display a proceed indication.

If, after all parts of the apparatus have again returned to their normal condition, an eastbound train enters section A—B, causing motor G to operate dog a to lock bar d, and if it is then desired that this train shall move over switch F¹ reversed to track Z instead of over its normal route to track Y, a trainman will insert crank N in the position in which it is shown in dash lines in the drawings, and will then operate crank N to disengage dog a from bar d. The placing of crank N in the position shown in dash lines opens contact 3, thereby breaking the stick circuit for relay I^G which, thereupon becoming deenergized, opens the operating circuits previously traced for motor G. Relay I^G can not again become energized, by its pick-up circuit previously traced, until the train has moved onto section B—C, deenergizing relay R^{2S}, nor until after the trainman removes crank N from the position shown in the drawings. The energization of relay I^G will then cause relay R^{2S} to become energized, after the train leaves section B—C, by its pick-up circuit which includes contact 6 of relay I^G.

Referring now to Fig. 2, all parts of the apparatus are shown in the normal condition, that is, switches F¹ and F² are in their normal position; each of the signals S¹, S², S⁵ and S⁶ is displaying a stop indication, and signals S³ and S⁴ are displaying a clear indication; each of the track sections is unoccupied; each of the relays H, I and W is deenergized except relay H³; and relays T are energized in the normal direction.

The circuit by which relay H³ is energized passes from terminal b, through front point of contact 50 of relay R², front point of contact 51 of relay T², contact 47 of dog a, back point of contact 52 of relay I^{LP}, front point of contact 53 of relay R³, contact 54 of relay H², and the winding of relay H³ to terminal o. With relay T² energized in the normal direction by its circuit, only a portion of which is shown, including contact 49 of relay R¹, and with relay H³ energized, green lamp G of signal S³ is lighted by its circuit passing from terminal b, through the front point of contact 11 of relay H³, contact 81 of relay T² in its normal position, and green lamp G of signal S³ to terminal o. Green lamp G of signal S⁴ is lighted by a similar circuit not shown in the drawings. Relay T⁶ for controlling signal S⁶ is energized in the normal direction by a circuit passing from terminal b¹ of a second source of current not shown in the drawings, through contact 63 of switch F¹, front point of contact 68 of relay R², front point of contact 70 of relay H³, contact 82 of relay R⁴, winding of relay T⁶, and the front point of contact 71 of relay H³ to terminal o¹ of the second source of current.

I will now assume that an eastbound train deenergizes relay T², which then opens, at the front point of its contact 51, the circuit previously traced for relay H³, causing relay H³ to become deenergized. A circuit will be thereby completed for energizing control element 59 of time element 40 device M, passing from terminal b, through the front point of contact 50 of relay R², back point of contact 51 of relay T², contact 55 of relay H², contact 56 of relay H³, contact 57 of relay I^R, back point of contact 58 of relay W^R, control element 45 59 of device M, contact 7 of switch F¹, contact 8 of crank N, and contact 21 of motor G in its normal position to terminal o. Upon the lapse of a measured period of time after control element 59 becomes energized, contact 60 of device M will close, thereby completing a circuit for energizing relay W^R, which is the same as the circuit traced for control element 59 of device M except that between contact 57 of relay I^R and contact 7 of switch F¹, it passes through contact 60 of device M and the winding of relay W^R. Relay W^R, upon becoming energized, completes its own stick circuit which is the same as its pick-up circuit just traced except that it includes the front point of its own contact 58 instead of contact 60 of device M. The opening of contact 58 of relay W^R at its back point deenergizes control element 59 of device M. Relay W^R, upon becoming energized, completes a reverse operating circuit for motor G, passing from terminal b, through the front point of contact 61 of relay W^R, armature 18 of motor G, back point of contact 62 of relay W^R, and field winding 22 of motor G to terminal o. Motor G thereupon moves dog a into engagement with bar d. Motor G, through its contact 21, opens the circuit traced for relay W^R, causing this relay to become deenergized when dog a reaches its final position for locking bar d.

Upon the completion of this operation of dog a, a circuit is completed for relay H¹, passing from

terminal b^1 , through contact 63 of switch F^1 , contact 26 of dog a , contact 64 of relay R^2 , contact 65 of relay T^1 , and the winding of relay H^1 to terminal o^1 . Relay H^1 , upon becoming energized, opens, at the back point of its contact 11, the circuit for red lamp R of signal S^1 , and completes, at the front point of its contact 11, a circuit for green lamp G of signal S^1 , through contact 12 of relay T^1 in its normal position.

10 The deenergization of relay H^3 , when relay T^2 becomes deenergized, causes contacts 70 and 71 of relay H^3 to reverse the polarity of the current supplied to relay T^6 by the circuit previously traced.

15 The train, upon entering section $B-C$, deenergizes relay R^2 which thereupon opens, at the front points of its contacts 64 and 68, the circuits traced for relays H^1 and T^6 , respectively, causing these relays to become deenergized. Relay H^1 is, however, slow releasing, and hence a pick-up circuit for relay I^L is closed for a brief period of time, said circuit passing from terminal b , through contact 28 of relay R^2 , contact 66 of relay H^1 , and the winding of relay I^L to terminal o . Relay I^L , upon becoming energized, completes its stick circuit which is the same as the pick-up circuit just traced except that it includes contact 31 of relay I^L instead of contact 66 of relay H^1 . Relay I^L , upon becoming energized, completes a second reverse energizing circuit for relay T^6 , which includes contact 69 of relay I^L instead of the front point of contact 68 of relay R^2 of the first reverse energizing circuit. Relay I^L , upon becoming energized, also completes a pick-up circuit for relay I^{LP} , passing from terminal b , through contact 73 of relay I^L , winding of relay I^{LP} , and push button contact U^1 to terminal o .

20 As the train proceeds further and enters section $C-D$, deenergizing relay R^3 , relay T^4 becomes deenergized on account of the opening of contact 49 of relay R^3 . Relay R^3 at this time also completes a stick circuit for relay I^{LP} , said circuit passing from terminal b , through contact 74 of relay R^3 , contact 75 of relay I^{LP} , winding of relay I^{LP} , and push button contact U^1 to terminal o . Relay I^{LP} , therefore remains energized as the train proceeds eastward through section $C-D$. The energization of relay I^{LP} holds open, at the back point of its contact 52, the circuit for energizing relay H^2 , and hence signal S^2 will not clear while the eastbound train is in section $C-D$.

25 When the train has left section $B-C$, relay W^N becomes energized by a circuit passing from terminal b , through the front point of contact 50 of relay R^2 , front point of contact 51 of relay T^2 , winding of relay W^N , and contact 21 of motor G in its reverse position. Relay W^N , upon becoming energized, completes a normal operating circuit for motor G , said circuit passing from terminal b , through the front point of contact 62 of relay W^N , armature 18 of motor G , back point of contact 61 of relay W^R , and field winding 22 of motor G to terminal o . Motor G thereupon operates dog a out of engagement with bar d .

30 I will now assume that all parts of the apparatus have again been returned to their normal condition, and that a westbound train passes signal S^2 which is now displaying a proceed indication. Relay R^2 thereupon becomes deenergized, opening, at the front point of its contact 50, the circuit previously traced for relay H^3 , and thereby causing relay H^3 to become deenergized. Relay H^3 being slow releasing, a pick-up circuit for relay I^R will be completed for a brief period, said circuit passing from terminal b , through the back

35 point of contact 50 of relay R^2 , front point of contact 79 of relay H^3 , winding of relay I^R , and push button U to terminal o . The energization of relay I^R causes a stick circuit to be completed for this relay, which is the same as the pick-up circuit just traced except that it includes contact 45 of relay I^R instead of contact 79 of relay H^3 .

40 As the train proceeds further and enters section $A-B$, a second stick circuit is completed for relay I^R , said circuit passing from terminal b , through contact 71 of relay T^2 , back point of contact 78 of relay H^2 , back point of contact 79 of relay H^3 , contact 45 of relay I^R , winding of relay I^R , and push button contact U to terminal o . Relay I^R will, therefore, continue energized as long as relay R^1 is deenergized, unless a trainman opens the stick circuit for relay I^R by operating push button U in the manner described in connection with Fig. 1. Motor G will, therefore, not be operated to move dog a into engagement with bar d , and signal S^1 will not be cleared, while the train is receding from signal S^1 .

45 From the foregoing description and the accompanying drawings, it follows that each of a few forms of apparatus embodying my invention comprises a track switch which is biased to a normal position, and which may be of the well known spring switch type; a device automatically operated for locking this switch in its normal position; an automatically operated traffic governing device for authorizing traffic movements in the facing direction over the switch, while the switch is in its normal position, if and only if the switch is locked; and an automatically controlled traffic governing device for authorizing traffic movements in the trailing direction over the switch if and only if the switch is unlocked.

50 I have described, for a few typical traffic movements, the operation of a few forms of apparatus embodying my invention. From these descriptions and from the accompanying drawings, the operation of the apparatus for every other possible traffic movement may be readily determined.

55 Although I have herein shown and described only two forms of railway traffic controlling apparatus embodying my invention, it is understood that various changes and modifications may be made therein within the scope of the appended claims without departing from the spirit and scope of my invention.

60 Having thus described my invention, what I claim is:

65 1. In combination, a railway track switch, means set into operation by a train approaching said switch from a given direction for locking said switch, a signal for governing traffic movements from said given direction over said switch, means set into operation by a train approaching said switch from said given direction for clearing said signal only if said switch is locked by said switch locking means, means set into operation by a train approaching said switch from a second direction for unlocking said switch, a second signal for governing traffic movements from said second direction over said switch, and means set into operation by a train approaching said switch from said second direction for clearing said second signal only if said switch is unlocked.

70 2. In combination, a railway track switch, means for at times locking said switch, means set into operation by a train approaching said switch for unlocking said switch, a signal for governing traffic movements over said switch, and means set into operation by a train approaching said switch for clearing said signal only if said switch

is unlocked and for completing the clearing of said signal only if said switch remains unlocked.

3. In combination, a railway track switch, means set into operation by a train approaching said switch from a given direction for locking said switch, means set into operation by a second train approaching said switch from a second direction for unlocking said switch, and directional means controlled by said second train for preventing operation of said locking means for locking said switch when said second train recedes from said switch.

4. In combination, a railway track switch, means set into operation by a train approaching said switch from a given direction for locking said switch, a signal for governing traffic movements from the opposite direction over said switch, means set into operation by a train approaching said signal from said opposite direction for clearing said signal, and directional means set into operation by a train moving over said switch from said first direction for preventing said signal from clearing when the train moving from said first direction recedes from said signal.

5. In combination, a railway track switch, means for at times locking said switch, a signal for governing traffic movements over said switch, a second signal for governing traffic movements over said switch, means set into operation by a train approaching said first signal for clearing said first signal only if said switch is locked, and means set into operation by a train approaching said second signal for clearing said second signal only if said switch is unlocked.

6. In combination, a railway track switch, an approach track section adjacent said switch, a time element device, means for energizing said time element device when a train enters said approach section if said switch is in the normal position, a switch relay, a circuit controlled by said time element device for energizing said switch relay upon the lapse of a measured period of time after said time element device becomes energized, and a circuit including a front contact of said switch relay for locking said switch in said normal position.

7. In combination, a railway track switch, a contact operated by said switch and arranged to be closed if and only if said switch is in its normal position, a locking device for locking said switch, an approach relay energized by a train approaching said switch, and a circuit including said switch operated contact and a front contact of

said approach relay for operating said locking device to lock said switch.

8. In combination, a railway track switch, a contact operated by said switch and arranged to be closed if and only if said switch is in its normal position, a locking device for locking said switch, an approach relay energized by a train approaching said switch, a circuit including said switch operated contact and a front contact of said approach relay for operating said locking device to lock said switch, a signal for governing traffic movements over said switch, and a circuit including a front contact of said approach relay and closed if and only if said switch is locked for clearing said signal.

9. In combination, a railway track switch, means for at times locking said switch, an approach relay energized if a train approaches said switch, a circuit including a front contact of said relay for operating said locking means to unlock said switch, a signal for governing traffic movements over said switch, and a circuit including a front contact of said approach relay and closed if and only if said switch is unlocked for clearing said signal.

10. In combination, a railway track switch, a control relay, a second control relay, means for selectively energizing said control relays, an electric circuit controlled by said first relay for locking said switch for traffic movements in a given direction over said switch in a given position when and only when said second relay is deenergized, and an electric circuit controlled by said second relay for unlocking said switch and for leaving said switch in the unlocked condition for traffic movements in the opposite direction over said switch in said given position.

11. In combination, a railway track switch, a normally energized relay deenergized by a train approaching said switch, a time element device, means controlled by said relay for setting said time element device into operation when said relay becomes deenergized, and means controlled by said time element device for locking said switch upon the lapse of a measured period of time after said relay becomes deenergized.

12. In combination, a railway track switch, a time element device, means controlled by a train approaching said switch for setting said time element device into operation, and means controlled by said time element device for locking said switch upon the lapse of a measured period of time after said time element device is set into operation.

HENRY S. YOUNG. 55
